3 Sheets-Sheet 1

<img alt="A detailed technical cross-sectional drawing of a mechanical device, labeled Fig. 5. The drawing shows a complex assembly of parts, including a central vertical shaft, various gears, and a locking mechanism. Numerous parts are labeled with numbers: 45, 46, 49, 51, 53, 32, 65, 55, 63, 68, 61, 59, 57, 77, 78, 58, 70, 34, 50, 47, 52, 48, 54, 30, 56, 64, 69, 62, 66, 67, 60, 59, 61, 63, 65, 67, 69, 71, 73, 75, 77, 79, 81, 83, 85, 87, 89, 91, 93, 95, 97, 99, 101, 103, 105, 107, 109, 111, 113, 115, 117, 119, 121, 123, 125, 127, 129, 131, 133, 135, 137, 139, 141, 143, 145, 147, 149, 151, 153, 155, 157, 159, 161, 163, 165, 167, 169, 171, 173, 175, 177, 179, 181, 183, 185, 187, 189, 191, 193, 195, 197, 199, 201, 203, 205, 207, 209, 211, 213, 215, 217, 219, 221, 223, 225, 227, 229, 231, 233, 235, 237, 239, 241, 243, 245, 247, 249, 251, 253, 255, 257, 259, 261, 263, 265, 267, 269, 271, 273, 275, 277, 279, 281, 283, 285, 287, 289, 291, 293, 295, 297, 299, 301, 303, 305, 307, 309, 311, 313, 315, 317, 319, 321, 323, 325, 327, 329, 331, 333, 335, 337, 339, 341, 343, 345, 347, 349, 351, 353, 355, 357, 359, 361, 363, 365, 367, 369, 371, 373, 375, 377, 379, 381, 383, 385, 387, 389, 391, 393, 395, 397, 399, 401, 403, 405, 407, 409, 411, 413, 415, 417, 419, 421, 423, 425, 427, 429, 431, 433, 435, 437, 439, 441, 443, 445, 447, 449, 451, 453, 455, 457, 459, 461, 463, 465, 467, 469, 471, 473, 475, 477, 479, 481, 483, 485, 487, 489, 491, 493, 495, 497, 499, 501, 503, 505, 507, 509, 511, 513, 515, 517, 519, 521, 523, 525, 527, 529, 531, 533, 535, 537, 539, 541, 543, 545, 547, 549, 551, 553, 555, 557, 559, 561, 563, 565, 567, 569, 571, 573, 575, 577, 579, 581, 583, 585, 587, 589, 591, 593, 595, 597, 599, 601, 603, 605, 607, 609, 611, 613, 615, 617, 619, 621, 623, 625, 627, 629, 631, 633, 635, 637, 639, 641, 643, 645, 647, 649, 651, 653, 655, 657, 659, 661, 663, 665, 667, 669, 671, 673, 675, 677, 679, 681, 683, 685, 687, 689, 691, 693, 695, 697, 699, 701, 703, 705, 707, 709, 711, 713, 715, 717, 719, 721, 723, 725, 727, 729, 731, 733, 735, 737, 739, 741, 743, 745, 747, 749, 751, 753, 755, 757, 759, 761, 763, 765, 767, 769, 771, 773, 775, 777, 779, 781, 783, 785, 787, 789, 791, 793, 795, 797, 799, 801, 803, 805, 807, 809, 811, 813, 815, 817, 819, 821, 823, 825, 827, 829, 831, 833, 835, 837, 839, 841, 843, 845, 847, 849, 851, 853, 855, 857, 859, 861, 863, 865, 867, 869, 871, 873, 875, 877, 879, 881, 883, 885, 887, 889, 891, 893, 895, 897, 899, 901, 903, 905, 907, 909, 911, 913, 915, 917, 919, 921, 923, 925, 927, 929, 931, 933, 935, 937, 939, 941, 943, 945, 947, 949, 951, 953, 955, 957, 959, 961, 963, 965, 967, 969, 971, 973, 975, 977, 979, 981, 983, 985, 987, 989, 991, 993, 995, 997, 999, 1001, 1003, 1005, 1007, 1009, 1011, 1013, 1015, 1017, 1019, 1021, 1023, 1025, 1027, 1029, 1031, 1033, 1035, 1037, 1039, 1041, 1043, 1045, 1047, 1049, 1051, 1053, 1055, 1057, 1059, 1061, 1063, 1065, 1067, 1069, 1071, 1073, 1075, 1077, 1079, 1081, 1083, 1085, 1087, 1089, 1091, 1093, 1095, 1097, 1099, 1101, 1103, 1105, 1107, 1109, 1111, 1113, 1115, 1117, 1119, 1121, 1123, 1125, 1127, 1129, 1131, 1133, 1135, 1137, 1139, 1141, 1143, 1145, 1147, 1149, 1151, 1153, 1155, 1157, 1159, 1161, 1163, 1165, 1167, 1169, 1171, 1173, 1175, 1177, 1179, 1181, 1183, 1185, 1187, 1189, 1191, 1193, 1195, 1197, 1199, 1201, 1203, 1205, 1207, 1209, 1211, 1213, 1215, 1217, 1219, 1221, 1223, 1225, 1227, 1229, 1231, 1233, 1235, 1237, 1239, 1241, 1243, 1245, 1247, 1249, 1251, 1253, 1255, 1257, 1259, 1261, 1263, 1265, 1267, 1269, 1271, 1273, 1275, 1277, 1279, 1281, 1283, 1285, 1287, 1289, 1291, 1293, 1295, 1297, 1299, 1301, 1303, 1305, 1307, 1309, 1311, 1313, 1315, 1317, 1319, 1321, 1323, 1325, 1327, 1329, 1331, 1333, 1335, 1337, 1339, 1341, 1343, 1345, 1347, 1349, 1351, 1353, 1355, 1357, 1359, 1361, 1363, 1365, 1367, 1369, 1371, 1373, 1375, 1377, 1379, 1381, 1383, 1385, 1387, 1389, 1391, 1393, 1395, 1397, 1399, 1401, 1403, 1405, 1407, 1409, 1411, 1413, 1415, 1417, 1419, 1421, 1423, 1425, 1427, 1429, 1431, 1433, 1435, 1437, 1439, 1441, 1443, 1445, 1447, 1449, 1451, 1453, 1455, 1457, 1459, 1461, 1463, 1465, 1467, 1469, 1471, 1473, 1475, 1477, 1479, 1481, 1483, 1485, 1487, 1489, 1491, 1493, 1495, 1497, 1499, 1501, 1503, 1505, 1507, 1509, 1511, 1513, 1515, 1517, 1519, 1521, 1523, 1525, 1527, 1529, 1531, 1533, 1535, 1537, 1539, 1541, 1543, 1545, 1547, 1549, 1551, 1553, 1555, 1557, 1559, 1561, 1563, 1565, 1567, 1569, 1571, 1573, 1575, 1577, 1579, 1581, 1583, 1585, 1587, 1589, 1591, 1593, 1595, 1597, 1599, 1601, 1603, 1605, 1607, 1609, 1611, 1613, 1615, 1617, 1619, 1621, 1623, 1625, 1627, 1629, 1631, 1633, 1635, 1637, 1639, 1641, 1643, 1645, 1647, 1649, 1651, 1653, 1655, 1657, 1659, 1661, 1663, 1665, 1667, 1669, 1671, 1673, 1675, 1677, 1679, 1681, 1683, 1685, 1687, 1689, 1691, 1693, 1695, 1697, 1699, 1701, 1703, 1705, 1707, 1709, 1711, 1713, 1715, 1717, 1719, 1721, 1723, 1725, 1727, 1729, 1731, 1733, 1735, 1737, 1739, 1741, 1743, 1745, 1747, 1749, 1751, 1753, 1755, 1757, 1759, 1761, 1763, 1765, 1767, 1769, 1771, 1773, 1775, 1777, 1779, 1781, 1783, 1785, 1787, 1789, 1791, 1793, 1795, 1797, 1799, 1801, 1803, 1805, 1807, 1809, 1811, 1813, 1815, 1817, 1819, 1821, 1823, 1825, 1827, 1829, 1831, 1833, 1835, 1837, 1839, 1841, 1843, 1845, 1847, 1849, 1851, 1853, 1855, 1857, 1859, 1861, 1863, 1865, 1867, 1869, 1871, 1873, 1875, 1877, 1879, 1881, 1883, 1885, 1887, 1889, 1891, 1893, 1895, 1897, 1899, 1901, 1903, 1905, 1907, 1909, 1911, 1913, 1915, 1917, 1919, 1921, 1923, 1925, 1927, 1929, 1931, 1933, 1935, 1937, 1939, 1941, 1943, 1945, 1947, 1949, 1951, 1953, 1955, 1957, 1959, 1961, 1963, 1965, 1967, 1969, 1971, 1973, 1975, 1977, 1979, 1981, 1983, 1985, 1987, 1989, 1991, 1993, 1995, 1997, 1999, 2001, 2003, 2005, 2007, 2009, 2011, 2013, 2015, 2017, 2019, 2021, 2023, 2025, 2027, 2029, 2031, 2033, 2035, 2037, 2039, 2041, 2043, 2045, 2047, 2049, 2051, 2053, 2055, 2057, 2059, 2061, 2063, 2065, 2067, 2069, 2071, 2073, 2075, 2077, 2079, 2081, 2083, 2085, 2087, 2089, 2091, 2093, 2095, 2097, 2099, 2101, 2103, 2105, 2107, 2109, 2111, 2113, 2115, 2117, 2119, 2121, 2123, 2125, 2127, 2129, 2131, 2133, 2135, 2137, 2139, 2141, 2143, 2145, 2147, 2149, 2151, 2153, 2155, 2157, 2159, 2161, 2163, 2165, 2167, 2169, 2171, 2173, 2175, 2177, 2179, 2181, 2183, 2185, 2187, 2189, 2191, 2193, 2195, 2197, 2199, 2201, 2203, 2205, 2207, 2209, 2211, 2213, 2215, 2217, 2219, 2221, 2223, 2225, 2227, 2229, 2231, 2233, 2235, 2237, 2239, 2241, 2243, 2245, 2247, 2249, 2251, 2253, 2255, 2257, 2259, 2261, 2263, 2265, 2267, 2269, 2271, 2273, 2275, 2277, 2279, 2281, 2283, 2285, 2287, 2289, 2291, 2293, 2295, 2297, 2299, 2301, 2303, 2305, 2307, 2309, 2311, 2313, 2315, 2317, 2319, 2321, 2323, 2325, 2327, 2329, 2331, 2333, 2335, 2337, 2339, 2341, 2343, 2345, 2347, 2349, 2351, 2353, 2355, 2357, 2359, 2361, 2363, 2365, 2367, 2369, 2371, 2373, 2375, 2377, 2379, 2381, 2383, 2385, 2387, 2389, 2391, 2393, 2395, 2397, 2399, 2401, 2403, 2405, 2407, 2409, 2411, 2413, 2415, 2417, 2419, 2421, 2423, 2425, 2427, 2429, 2431, 2433, 2435, 2437, 2439, 2441, 2443, 2445, 2447, 2449, 2451, 2453, 2455, 2457, 2459, 2461, 2463, 2465, 2467, 2469, 2471, 2473, 2475, 2477, 2479, 2481, 2483, 2485, 2487, 2489, 2491, 2493, 2495, 2497, 2499, 2501, 2503, 2505, 2507, 2509, 2511, 2513, 2515, 2517, 2519, 2521, 2523, 2525, 2527, 2529, 2531, 2533, 2535, 2537, 2539, 2541, 2543, 2545, 2547, 2549, 2551, 2553, 2555, 2557, 2559, 2561, 2563, 2565, 2567, 2569, 2571, 2573, 2575, 2577, 2579, 2581, 2583, 2585, 2587, 2589, 2591, 2593, 2595, 2597, 2599, 2601, 2603, 2605, 2607, 2609, 2611, 2613, 2615, 2617, 2619, 2621, 2623, 2625, 2627, 2629, 2631, 2633, 2635, 2637, 2639, 2641, 2643, 2645, 2647, 2649, 2651, 2653, 2655, 2657, 2659, 2661, 2663, 2665, 2667, 2669, 2671, 2673, 2675, 2677, 2679, 2681, 2683, 2685, 2687, 2689, 2691, 2693, 2695, 2697, 2699, 2701, 2703, 2705, 2707, 2709, 2711, 2713, 2715, 2717, 2719, 2721, 2723, 2725, 2727, 2729, 2731, 2733, 2735, 2737, 2739, 2741, 2743, 2745, 2747, 2749, 2751, 2753, 2755, 2757, 2759, 2761, 2763, 2765, 2767, 2769, 2771, 2773, 2775, 2777, 2779, 2781, 2783, 2785, 2787, 2789, 2791, 2793, 2795, 2797, 2799, 2801, 2803, 2805, 2807, 2809, 2811, 2813, 2815, 2817, 2819, 2821, 2823, 2825, 2827, 2829, 2831, 2833, 2835, 2837, 2839, 2841, 2843, 2845, 2847, 2849, 2851, 2853, 2855, 2857, 2859, 2861, 2863, 2865, 2867, 2869, 2871, 2873, 2875, 2877, 2879, 2881, 2883, 2885, 2887, 2889, 2891, 2893, 2895, 2897, 2899, 2901, 2903, 2905, 2907, 2909, 2911, 2913, 2915, 2917, 2919, 2921, 2923, 2925, 2927, 2929, 2931, 2933, 2935, 2937, 2939, 2941, 2943, 2945, 2947, 2949, 2951, 2953, 2955, 2957, 2959, 2961, 2963, 2965, 2967, 2969, 2971, 2973, 2975, 2977, 2979, 2981, 2983, 2985, 2987, 2989, 2991, 2993, 2995, 2997, 2999, 3001, 3003, 3005, 3007, 3009, 3011, 3013, 3015, 3017, 3019, 3021, 3023, 3025, 3027, 3029, 3031, 3033, 3035, 3037, 3039, 3041, 3043, 3045, 3047, 3049, 3051, 3053, 3055, 3057, 3059, 3061, 3063, 3065, 3067, 3069, 3071, 3073, 3075, 3077, 3079, 3081, 3083, 3085, 3087, 3089, 3091, 3093, 3095, 3097, 3099, 3101, 3103, 3105, 3107, 3109, 3111, 3113, 3115, 3117, 3119, 3121, 3123, 3125, 3127, 3129, 3131, 3133, 3135, 3137, 3139, 3141, 3143, 3145, 3147, 3149, 3151, 3153, 3155, 3157, 3159, 3161, 3163, 3165, 3167, 3169, 3171, 3173, 3175, 3177, 3179, 3181, 3183, 3185, 3187, 3189, 3191, 3193, 3195, 3197, 3199, 3201, 3203, 3205, 3207, 3209, 3211, 3213, 3215, 3217, 3219, 3221, 3223, 3225, 3227, 3229, 3231, 3233, 3235, 3237, 3239, 3241, 3243, 3245, 3247, 3249, 3251, 3253, 3255, 3257, 3259, 3261, 3263, 3265, 3267, 3269, 3271, 3273, 3275, 3277, 3279, 3281, 3283, 3285, 3287, 3289, 3291, 3293, 3295, 3297, 3299, 3301, 3303, 3305, 3307, 3309, 3311, 3313, 3315, 3317, 3319, 3321, 3323, 3325, 3327, 3329, 3331, 3333, 3335, 3337, 3339, 3341, 3343, 3345, 3347, 3349, 3351, 3353, 3355, 3357, 3359, 3361, 3363, 3365, 3367, 3369, 3371, 3373, 3375, 3377, 3379, 3381, 3383, 3385, 3387, 3389, 3391, 3393, 3395, 3397, 3399, 3401, 3403, 3405, 3407, 3409, 3411, 3413, 3415, 3417, 3419, 3421, 3423, 3425, 3427, 3429, 3431, 3433, 3435, 3437, 3439, 3441, 3443, 3445, 3447, 3449, 3451, 3453, 3455, 3457, 3459, 3461, 3463, 3465, 3467, 3469, 3471, 3473, 3475, 3477, 3479, 3481, 3483, 3485, 3487, 3489, 3491, 3493, 3495, 3497, 3499, 3501, 3503, 3505, 3507, 3509, 3511, 3513, 3515, 3517, 3519, 3521, 3523, 3525, 3527, 3529, 3531, 3533, 3535, 3537, 3539, 3541, 3543, 3545, 3547, 3549, 3551, 3553, 3555, 3557, 3559, 3561, 3563, 3565, 3567, 3569, 3571, 3573, 3575, 3577, 3579, 3581, 3583, 3585, 3587, 3589, 3591, 3593, 3595, 3597, 3599, 3601, 3603, 3605, 3607, 3609, 3611, 3613, 3615, 3617, 3619, 3621, 3623, 3625, 3627, 3629, 3631, 3633, 3635, 3637, 3639, 3641, 3643, 3645, 3647, 3649, 3651, 3653, 3655, 3657, 3659, 3661, 3663, 3665, 3667, 3669, 3671, 3673, 3675, 3677, 3679, 3681, 3683, 3685, 3687, 3689, 3691, 3693, 3695, 3697, 3699, 3701, 3703, 3705, 3707, 3709, 3711, 3713, 3715, 3717, 3719, 3721, 3723, 3725, 3727, 3729, 3731, 3733, 3735, 3737, 3739, 3741, 3743, 3745, 3747, 3749, 3751, 3753, 3755, 3757, 3759, 3761, 3763, 3765, 3767, 3769, 3771, 3773, 3775, 3777, 3779, 3781, 3783, 3785, 3787, 3789, 3791, 3793, 3795, 3797, 3799, 3801, 3803, 3805, 3807, 3809, 3811, 3813, 3815, 3817, 3819, 3821, 3823, 3825, 3827, 3829, 3831, 3833, 3835, 3837, 3839, 3841, 3843, 3845, 3847, 3849, 3851, 3853, 3855, 3857, 3859, 3861, 3863, 3865, 3867, 3869, 3871, 3873, 3875, 3877, 3879, 3881, 3883, 3885, 3887, 3889, 3891, 3893, 3895, 3897, 3899, 3901, 3903, 3905, 3907, 3909, 3911, 3913, 3915, 3917, 3919, 3921, 3923, 3925, 3927, 3929, 3931, 3933, 3935, 3937, 3939, 3941, 3943, 3945, 3947, 3949, 3951, 3953, 3955, 3957, 3959, 3961, 3963, 3965, 3967, 3969, 3971, 3973, 3975, 3977, 3979, 3981, 3983, 3985, 3987, 3989, 3991, 3993, 3995, 3997, 3999, 4001, 4003, 4005, 4007, 4009, 4011, 4013, 4015, 4017, 4019, 4021, 4023, 4025, 4027, 4029, 4031, 4033, 4035, 4037, 4039, 4041, 4043, 4045, 4047, 4049, 4051, 4053, 4055, 4057, 4059, 4061, 4063, 4065, 4067, UNITED STATES PATENT OFFICE

GERRIT VANDERBEEK, OF BELOIT, WISCONSIN, ASSIGNOR TO YATES-AMERICAN MACHINE COMPANY, OF BELOIT, WISCONSIN, A CORPORATION OF DELAWARE

BORING MACHINE

Application filed October 12, 1929. Serial No. 399,180.

This invention has to do with multiple bit boring machines of the type in which the work is placed on a vertically reciprocating table and raised into engagement with the bits.

Heretofore, in using machines of the type under consideration, difficulty has been experienced in getting the bits to bore to the desired depth with any degree of uniformity, owing to the fact that the resistance offered by different pieces of work varies considerably because of hard spots, knots, grain irregularities, etc., in the same, and it is almost impossible to make the portion of the frame which supports the bits sufficiently rigid to prevent the same from yielding under the stresses set up at the instant that the table passes through the uppermost portion of its movement. Furthermore, in the machines heretofore used, it has been the practice to raise and lower the table mechanically, and difficulty has been experienced in working out a satisfactory control for the same.

The object of the present invention is to provide a multiple bit boring machine in which the bits will always bore to the full depth for which set regardless of the resistance encountered; in which the table for the work is raised and lowered by hydraulic power; and in which the movement of the table may be controlled either automatically, semi-automatically, or manually, as desired.

While the foregoing statements are indicative in a general way of the nature of the invention, other objects and advantages will be apparent to those skilled in the art upon a full understanding of the construction, arrangement and operation of the improvements constituting the subject matter of the invention.

One form of the invention is presented herein for the purpose of exemplification, but it will of course be appreciated that the invention is susceptible of embodiment in other structurally modified forms coming equally within the scope of the appended claims.

In the accompanying drawings:

Fig. 1 is a perspective view of a multiple bit boring machine equipped with the table operating and controlling means of the invention;

Fig. 2 is a fragmentary end view of the machine;

Fig. 3 is a fragmentary horizontal section, taken on the line 3-3 of Fig. 2;

Fig. 4 is a fragmentary vertical section, 55 taken on the line 4-4 of Fig. 3; and

Fig. 5 is a fragmentary vertical section, taken on the line 5-5 of Fig. 4.

The machine which is shown in the drawings includes a frame 10, a number of rotating bits 11, and a vertically reciprocating table 12 on which the work to be bored is placed and raised into engagement with the bits. The bits 11 are carried by the upper portion of the frame, and may be arranged, mounted and operated in accordance with well known practice or in any other desired manner. The table 12 is supported in the lower portion of the frame, and is provided at its ends with downwardly extending slide plates 13 which travel up and down between spaced parallel guide strips 14.

The table 12 is raised and lowered by oil or other suitable liquid, the oil being forced under pressure by a motor driven pump 15 into first one end of a cylinder 16 and then the other through pipes 17 and 18 which extend from the pump to the ends of the cylinder. The cylinder 16 contains a closely fitting piston 19, and a long piston rod 20 is attached to the piston and extends forwardly from the front end of the cylinder into a casing 21, where it is connected at 22 with the free end of a lever 23 which is secured to a long sturdy rock shaft 24. The rock shaft 24 is journaled in the ends of the frame beneath the table and carries two levers 25 which are secured to the rock shaft adjacent the ends of the same and are connected with the previously mentioned slides 13 by links 26.

From the description thus far, it will be understood that when the oil is fed to the cylinder 16 through the pipe 17 the table 12 will be raised, and when the oil is fed to the cylinder through the pipe 18 the table will be lowered. The flow of the oil, first through the pipe 17 and then through the pipe 18, is initiated by changes made in the position of a rod 27, which rod operates a

slide valve 28 of well known construction communicating with the pump 15 and the pipes 17 and 18. When the rod 27 is placed in an intermediate position, the valve will prevent any of the oil from being forced through either the pipe 17 or the pipe 18. When the rod 27 is shifted to the left, into what will be hereinafter referred to as the raising position, the valve will open communication between the pump and the pipe 17. When the rod is shifted to the right, in what will be called the lowering position, the valve will establish communication between the pump and the pipe 18. In the particular position shown in Fig. 2, the valve is set to establish communication between the pump and the pipe 17, and the table 12 is therefore in the act of commencing its upward movement.

The movement of the table 12 is determined by the position in which an easily manipulated control rod 29 is placed by the operator. The control rod 29 extends along the front of the machine below the level of the table and is provided with one or more conveniently located handles 30. The control rod may be oscillated in either direction, or it may be shifted axially into any one of three different positions. The right end of the control rod is both rotatably and slidably supported in a bearing bracket 31 which is attached to the frame, while the left end telescopically telescopes over and is non-rotatably splined with a short continuation shaft 32 which is journaled in a bracket 33 on the frame.

The telescoping portions of the control rod 29 and the shaft 32 are enclosed within a housing 34 which is mounted on the bracket 33, and the left end of the shaft 32 is keyed to a short upwardly extending arm 35 which is pivoted at its upper end to the front end of a rearwardly extending rod 36. The rod 36 is supported adjacent its rear end in a freely sliding sleeve 37 which is pivoted to the upper end of an arm 38 on the left end of the rock shaft 24. When the rock shaft oscillates in raising or lowering the table, the sleeve 37 slides along the rod 36 between two adjustably positioned abutment lugs 39 and 40 on the rod. When the table 12 reaches the upper end of its travel, the sleeve 37 moves into engagement with the lug 39 and shifts the rod 36 rearwardly a short distance, and, when the table reaches the lower end of its travel, the sleeve moves into engagement with the lug 40 and shifts the rod forwardly a short distance.

The previously described valve rod 27 is connected by a short link 41 to one arm 42 of a bell-crank lever which is journaled in the adjacent end of the frame, and the other arm 43 of the bell-crank lever, which is located on the inside of the frame and extends in the opposite direction from the arm

42, is pivoted at 44 to the rear end of a forwardly extending rod 45. The front end of the rod 45 is pivoted at 46 to the upper end of a tiltable block 47 which is positioned within the housing 34, and the lower portion of the block is rotatably mounted on a bushing 48 which is keyed to the previously described shaft 32. Any relative rotation between the block 47 and the bushing 48 is yieldingly resisted by the action of two springs 49 and 50. The springs are compressed in bores in the block by two plungers 51 and 52 which are pivoted to the bushing 48 in recesses 53 and 54 formed in opposite sides of the same.

The block 47 is provided with two segments 55 and 56 which are partially set into the periphery of the block to present latching abutments for coaction with the two dogs 57 and 58. The dogs are pivoted at 59 and 60 to the bracket 33 and are urged toward the periphery of the block by springs 61 and 62. The dogs are provided adjacent their front ends with shoulders 63 and 64 which interlock respectively with the lower ends of the segments 55 and 56. The segments are arranged with the lower ends thereof a little closer together than the shoulders on the dogs, so that the block cannot be latched against movement in both directions at the same time.

The segments are released at certain times from the dogs by means of two cams 65 and 66 which are adjustably fastened to a plate 67 which is keyed to the shaft 32 at the right ends of the block 47 and the bushing 48. The cams are adapted to ride under two rollers 68 and 69 on the free ends of the dogs, whereby to force the latter out away from the segments when the shaft 32 is oscillated far enough in either direction to bring one of the cams into contact with one of the rollers.

Either the dog 58 alone, or the dogs 57 and 58 together, may be swung back away from the segments into inoperative positions through the instrumentality of a pin 70, which pin passes loosely through a guide aperture 71 in the lower portion of the housing 34. The pin 70 is provided intermediate its ends with a beveled shoulder 72 which merges into a portion 73 of increased diameter, and is carried by a bracket 74 which is journaled between two confining collars 75 and 76 on the left end of the control shaft 29. When the control shaft is merely oscillated in one direction or the other, without being shifted axially, the pin 70 does not move at all, but, when the control shaft is shifted axially, the pin obviously shifts with it. At points above the pin 70, the dogs 57 and 58 are provided with tail portions 77 and 78, which portions are cammed by the beveled shoulders 72 on the pin up onto the enlarged portion 73 of the pin when the latter is shifted toward the left. When the pin is in the extreme right position shown in Fig. 4, both of the dogs are free to

interlock with the segments. When the pin is shifted by the control rod 29 into an extreme left position, both dogs are rendered inoperative. When the pin is shifted by the 5 control rod into an intermediate position, only the dog 57 is free to latch with the segment 55, the dog 58 being rendered inoperative by reason of the fact that the tail portion on that dog is opposite the enlarged portion of the 10 pin and is consequently held in an outwardly cammed position against the action of the spring 62.

The control mechanism above described may be quickly and easily set by the operator 15 for either automatic, semi-automatic or manual operation of the machine.

To operate the machine manually, the control rod 29, with the handles 30 thereon maintained in a horizontal position, is shifted to 20 the left as far as it will go, thereby causing both of the locking dogs 57 and 58 to be swung out away from the paths of travel of the segments 55 and 56 into inoperative positions. As long as the handles 30 on the control shaft 25 are in a horizontal position, the table 12 will remain stationary, but as soon as the control shaft is oscillated by the operator into a position wherein the handles are inclined downwardly, the resistance of the springs 49 and 30 50 will cause the block 47 to be correspondingly tilted, with the result that the rod 45 will act on the rod 27 through the arms 42 and 43 of the bell-crank lever to shift the valve 28 into a position wherein the pipe 17 is 35 placed in communication with the pump 15, causing the table to move upwardly.

When the table reaches the upper end of its travel, the sleeve 37 rides against the lug 39 and shifts the rod 36 rearwardly, thereby 40 turning the control shaft back into its neutral position. Since the springs 49 and 50 cause the block 47 to turn with the control rod, the rods 27 and 45 are consequently shifted back into their neutral positions, and the valve 28, 45 as a result, closes off communication between the pump and the pipe 17, bringing the table instantly to rest in its uppermost position. The uppermost position of the table is determined by the setting of the adjustable lug 39 50 on the rod 36. Similarly, the lowermost position is determined by the setting of the adjustable lug 40.

To bring the table down again whenever desired, it is merely necessary to swing one of 55 the handles on the control rod into an upwardly inclined position, whereupon the block 47 will be tilted rearwardly and the rods 45 and 27 will cause the valve 28 to shift into a position wherein the pump is placed 60 in communication with the pipe 18.

At any time during either the upward or the downward travel of the table, the operator may instantly stop the same by merely swinging one of the handles on the control 65 rod back again into a horizontal position,

since the control rod, as long as the dogs 57 and 58 remain inoperative, acts through the springs 49 and 50, the block 47 and the rods 45 and 27 to neutralize the valve. The table can also be started upwardly or downwardly 70 from any position in which it has been stopped by merely swinging one of the handles on the control rod into either a downwardly inclined position or an upwardly inclined position, depending on the direction of movement desired. When the handle is swung downwardly, the table will go up, and, when the handle is swung upwardly, the table will go down.

To cause the machine to operate automatically, with the table traveling continuously up and down without stopping, the control rod, with the handles extending horizontally, is shifted to the right as far as it will go, thereby causing the pin 70 to release the dogs 57 80 and 58 and allow the free ends of the dogs to press against the outer faces of the segments 55 and 56. One of the handles 30 is then swung downwardly, whereby to tilt the block 47 forwardly into the position shown in Fig. 90 5, in which position the shoulder 63 on the dog 57 interlocks with the lower edge of the segment 55 and prevents return movement of the block. As soon as the block 47 assumes such position, the table commences its upward travel.

When the table reaches the upper end of its movement, the sleeve 37 moves into engagement with the lug 39 on the rod 36 and shifts the rod rearwardly, causing the shaft 32, 100 together with the bushing 48 and the control rod 29, to oscillate in a counter-clockwise direction as viewed from the left end of the machine. During the first part of such oscillation, the block 47 is prevented by the dog 57 from moving, but, after the oscillation has progressed to the point where the cam 65 has moved downwardly into contact with the roller 68 on the dog 57, during which time the spring 50 has become compressed, the dog 57 is tripped from the segment 55 and the energy stored up in the spring 50 kicks the block over through a greater angle than the bushing 48 would have turned it were it not latched, the extent to which the block 47 110 is thus tilted to the rear being great enough to allow the shoulder 64 on the free end of the other dog 58 to engage under and interlock with the lower edge of the segment 56, whereby to hold the block in that position. 120 The block 47, when tilted rearwardly by the spring 50, shifts the valve 28 past the neutral position to the position wherein the pipe 18 is placed in communication with the pump, with the result that the table starts to move 125 downwardly.

When the table reaches its lowermost position, the sleeve 37 moves into engagement with the lug 40 on the rod 36, causing the shaft 32, together with the bushing 48 and 130

the control rod 29, to be oscillated in a clockwise direction as viewed from the left end of the machine. During the first part of such oscillation, the block 47 is prevented from 5 moving with the bushing because of the interlocked relation between the segment 56 and the dog 58, but, when the cam 66 reaches the roller 69 on the dog 58, it forces the free end of the dog outwardly away from the segment 10 and allows the spring 49, which has been compressed by the stationary condition of the block, to forcibly kick the block over beyond the position to which the bushing would normally carry it and into the latched position 15 shown in Fig. 5, whereupon the cycle above described is automatically repeated, the table raising and lowering continuously without attention until stopped by the action of the operator in shifting the control rod 20 29 to the left.

To obtain a semi-automatic operation of the machine—wherein the table comes to rest in its lowermost position after moving up and down once—the control rod 29, with the handles 30 extending horizontally, is shifted axially into a position midway between the previously described automatic and manual control positions, thereby causing the pin 70 to hold only the dog 58 out of operation. One 25 of the handles 30 is then swung downwardly far enough to allow the shoulder 63 on the dog 57 to catch under the lower end of the segment 55, whereupon the pipe 17 is placed in communication with the pump 15 by the 30 valve 28 and the table commences to travel upwardly.

When the table reaches its uppermost position, the sleeve 37 acts through the lug 39 and rod 36 to oscillate the shaft 32, bushing 48 and control rod 29 in a counterclockwise direction, and, as soon as the cam 65 reaches the roller 68 on the dog 57 and releases the latter, the compression built up in the spring 50 forcibly kicks the block 47 far 45 enough rearwardly to shift the valve 28 past the neutral or shut off position into a position wherein the pump is placed in communication with the pipe 18, causing the table to descend. Since the dog 58 is being held by 50 the pin 70 in an inoperative position, the block does not become latched in such rearwardly tilted position.

When the table thereafter reaches its lowest position, the sleeve 37 acts to oscillate the shaft 32, bushing 48 and control rod 29 in a clockwise direction, and the springs 49 and 50 cause the block 47 to oscillate with the bushing. As soon as the block has moved far enough to shift the valve 28 into neutral, the 55 flow of oil to the cylinder ceases and the table comes to rest, in readiness for another such cycle of operation as soon as one of the handles 30 is again depressed by the operator.

If desired, in the semi-automatic operation 60 of the machine, a foot pedal 79 may be used

to initiate each cycle of operation. The pedal 79 is pivoted to the bottom of the frame at 80 and is provided with an upwardly extending link 81 which has a longitudinally extending slot 82 in its upper end. An arm 83 is secured to the control shaft 29 and is provided at its free end with a pin 84 which extends laterally into the slot in the link. When the pedal 79 is depressed, the lower end of the slot 82 engages with the pin 84 and swings 75 the arm 83 upwardly to oscillate the control shaft in the same direction as the handles 30 oscillate it when swung into downwardly inclined positions, the extra length of the slot 82 serving to permit the pedal 79 to immediately reassume its initial position.

As the table approaches the uppermost end of its travel, the resistance offered by the stock in engagement with the bits becomes 80 exceedingly great. In the ordinary mechanically operated boring machine, the portion of the frame of the machine supporting the bits, even though sturdily constructed, will frequently yield a little under such resistance in a direction away from the table as the latter passes through the upper most part of its movement, which yield is particularly pronounced when hard spots are encountered in the stock by one or more of the bits, with the result that there is very often a lack of 85 uniformity in the depth of the holes bored in different pieces of stock operated on by the same boring machine with the same adjustment of bits.

This difficulty is avoided in the present 90 machine. The table 12 is raised and lowered by hydraulic power, and a relief valve 85 of suitable construction is placed in the pipe 18 and is connected with a line 86 leading back to the low pressure side of the pump. When the resistance offered by the stock in engagement with the bits becomes excessive at the speed at which the table is moving, the valve 95 85 bi-passes through the line 86 some of the oil being forced through the pipe 17, and the table slows up or even momentarily stops to allow the bits to fully complete their boring 100 operation by the time that the table reaches its uppermost position and starts down.

I claim:

1. In a boring machine, a plurality of bits, a work support, means for moving the support toward and away from the bits, means for automatically reversing the direction of movement of the support at both ends of 105 its travel, manually actuated means for rendering the automatic reversing means inoperative, separately operable manually actuated means for starting and stopping the movement of the support in any position thereof, and a single control member connected with the two last mentioned means for at will independently operating the same.

2. In a boring machine, a plurality of bits, a work support, means for moving the sup- 110

port toward and away from the bits, means for automatically reversing the direction of movement of the support at both ends of its travel, manually actuated means for rendering the automatic reversing means inoperative, 5 manually actuated means for starting and stopping the movement of the support, and a single control member connected with the two last mentioned means for operating the same, 10 said control member being shiftable in the direction of its axis to operate one of said means and being rotatable about its axis to operate the other.

3. In a boring machine, a plurality of bits, 15 a work support, means for moving the support toward and away from the bits, means for automatically reversing the direction of movement of the support at both ends of its travel, manually actuated means for rendering the automatic reversing means inoperative, 20 manually actuated means for starting and stopping the movement of the support, and a single control rod connected with the two last mentioned means for operating the 25 same, said rod being shifted in the direction of its axis to operate the former and being rotated about its axis to operate the latter.

4. In a boring machine, a plurality of bits, 30 a work support movable toward and away from the bits, a cylinder, a piston in the cylinder, a connection between the piston and the support for transmitting the movement of the piston to the support, a valve for delivering fluid under pressure to either end of 35 the cylinder to move the piston, and a control rod connected with the valve to operate the latter, said rod being rotatable about its axis into one position to cause the table to travel upwardly, being rotatable into another position 40 to cause the table to travel downwardly, being rotatable into still another position to cause the table to come to rest, and being shiftable axially to cause the table to automatically reverse its direction of movement 45 when it reaches a predetermined point in its upward travel.

5. In a boring machine, a plurality of vertically disposed bits arranged in a horizontally elongated group, a horizontally elongated work support beneath the bits movable toward and away from the latter, a cylinder, 50 a piston in the cylinder, connections between the piston and the ends of the support for transmitting the movement of the piston equally to both ends of the support, a valve for delivering fluid under pressure to either end of the cylinder to move the piston, and a manually operable control rod extending lengthwise of the support below and in front 55 of the latter for operating the valve, said rod being movable into one position to cause the support to automatically reverse its direction of movement at predetermined points in both its upward and downward travel and 60 being movable into another position to cause 65

the support to automatically reverse its direction of movement at a predetermined point in only its upward travel.

6. In a boring machine, a plurality of vertically disposed bits arranged in a horizontally elongated group, a horizontally elongated work support beneath the bits movable toward and away from the latter, a hydraulic cylinder, a piston in the cylinder, connections between the piston and the ends of the support for transmitting the movement of the piston equally to both ends of the support, a valve for delivering fluid under pressure to either end of the cylinder to move the piston, and a control member connected with the valve to operate the latter, said control member being movable into one position to cause the support to automatically reverse its direction of movement at predetermined points in both its upward and downward travel and being movable into another position to cause the support to automatically reverse its direction of movement at a predetermined point in only its upward travel.

7. In a boring machine, a horizontally elongated frame having vertically spaced upper and lower portions, a horizontally elongated group of vertically disposed bits mounted on the upper portion of the frame, a horizontally elongated work-supporting table mounted on the lower portion of the frame beneath the bits for vertical movement toward and away from the latter, a horizontally extending shaft journaled in the lower portion of the frame below the table, means for rotating the shaft in opposite directions, connections between the shaft and the table adjacent the ends of the latter for raising the table when the shaft is turned in one direction and lowering the table when the shaft is turned in the other direction, and manually actuated means for controlling the starting, stopping and direction of rotation of the shaft.

8. In a boring machine, a horizontally elongated frame having vertically spaced upper and lower portions, a horizontally elongated group of vertically disposed bits mounted on the upper portion of the frame, a horizontally elongated work-supporting table mounted on the lower portion of the frame beneath the bits for vertical movement toward and away from the latter, a horizontally extending shaft journaled in the lower portion of the frame below the table, connections between the shaft and the table adjacent the ends of the latter for moving the table vertically when the shaft is oscillated, a hydraulic cylinder mounted on the lower portion of the frame below the table, a piston in the cylinder, a connection between the piston and the shaft for turning the shaft when the piston is moved, a valve for introducing fluid under pressure into either end of the cylinder to cause movement of the piston and consequent movement of the table, and actuating means

for the valve including a manually operable control member mounted on the front of the lower portion of the frame adjacent the table.

9. In a boring machine, a horizontally elongated frame having vertically spaced upper and lower portions, a horizontally elongated group of vertically disposed bits mounted on the upper portion of the frame, a horizontally elongated work-supporting table mounted on the lower portion of the frame beneath the bits for vertical movement toward and away from the latter, a horizontally extending shaft journaled in the lower portion of the frame below the table, connections between the shaft and the table adjacent the ends of the latter for moving the table vertically when the shaft is oscillated, a hydraulic cylinder mounted on the lower portion of the frame below the table, a piston in the cylinder, a connection between the piston and the shaft for turning the shaft when the piston is moved, a valve for introducing fluid under pressure into either end of the cylinder to cause movement of the piston and consequent movement of the table, and actuating means for the valve including a manually operable control rod mounted on the frame in a position lengthwise of the latter below and in front of the table for operation from any one of several locations.

In witness whereof I have hereunto subscribed my name.

GERRIT VANDERBEEK.
